US0D1108537S

(12) **United States Design Patent** (10) **Patent No.:** **US D1,108,537 S**
(45) **Date of Patent:** **** Jan. 6, 2026**

(54) **INK BOTTLE**

(71) Applicant: **BROTHER INDUSTRIES, LTD.**,
Nagoya (JP)

(72) Inventors: **Masahiro Hayashi**, Anjo (JP);
Hirohide Nawata, Nagoya (JP);
Fumiya Nakamura, Nagoya (JP);
Yuma Tanabe, Nagoya (JP); **Satoru Oki**, Nagoya (JP); **Yuji Fukuta**, Nagoya (JP); **Naoya Okazaki**, Kasamatsu (JP)

(73) Assignee: **BROTHER INDUSTRIES, LTD.**,
Nagoya (JP)

(**) Term: **15 Years**

(21) Appl. No.: **29/922,002**

(22) Filed: **Dec. 20, 2023**

(30) **Foreign Application Priority Data**

Jun. 20, 2023 (JP) ..... 2023-012570 D

(57) **CLAIM**

The ornamental design for an ink bottle as shown and described.

DESCRIPTION

FIG. 1 is a perspective view of the ink bottle;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof; and,

FIG. 7 is a bottom plan view thereof.

The broken lines depict parts of the ink bottle that form no part of the claimed design.

1 Claim, 7 Drawing Sheets
